ELECTRICAL WEFT DETECTOR AND
SHUTTLE THEREFOR

Richard Greenleaf Turner, Worcester, Mass., assignee to Crompton & Knowles Loom Works, Worcester, Mass., a corporation of Massachusetts

Application January 26, 1933, Serial No. 653,642

10 Claims. (Cl. 139—205)

This invention relates to improvements in electrical weft detectors and shuttles for weft replenishing looms and it is the general object of the invention to provide a durable shuttle, effective upon exhaustion of weft to complete a loom controlling electric circuit through the detector fingers which are external to the shuttle.

Shuttles of the electrical indicating type have ordinarily employed a pair of contact plates mounted on the front wall of the shuttle to engage brush or sliding contacts carried by the shuttle box. Several interconnected parts are carried within the shuttle to constitute a circuit having its terminals attached to the plates. The constant jarring incident to the abrupt stopping of the shuttle loosens and breaks these parts, so that they provide poor contact with resultant misindication. It is an important object of my present invention to provide a shuttle which has a circuit closer or contact plate normally in non-indicating position, but movable at exhaustion of weft to a position where it can electrically connect opposite poles of an indicating circuit all of which, except the closer, is located exteriorly of the shuttle. By the use of my improved shuttle current is not required to flow through any joint or mechanical connection carried permanently by the shuttle.

It is a further object of my invention to provide a shuttle so constructed that the aforesaid contact plate can be given a relatively large motion at the time of weft exhaustion, thereby avoiding the necessity for setting parts for close operation.

It is another object of my invention to provide the lever which carries the contact plate with stops to limit the movement of the plate toward indicating position. These stops are made effective to move the yarn engaging detecting part of the lever out of the path of movement of the weft carrier when the spindle is raised to receive a fresh supply of weft.

It is another object of my invention to provide a stop for at least one of the electrodes external to the shuttle, said stops being positioned to engage the shuttle regardless of the vertical position of the latter in the shuttle box and thus prevent closing of the circuit until the contact plate has reached a predetermined position. In this way the detector is enabled to operate properly even though the shuttle be misplaced.

In connection with my improved shuttle I employ a form of detector having two electrodes which are above the shuttle and are moved down in any approved manner after the shuttle is

boxed, thereby avoiding all rubbing contact between a shuttle part and the external circuit. In prior constructions a sliding of the contact plates along the binder or box back has resulted in accumulation on the plates of grit and dirt which is carried into and occasionally dropped within the shed of the loom. Such grit usually carries a small amount of oil which cannot be removed from the fabric so that the latter is permanently injured. With my improved shuttle, on the other hand, no opportunity arises for the formation of the grit or dirt, and as a result a higher grade of cloth can be woven.

It is a further important object of my invention to provide the shuttle with means for holding the indicator in indicating position. In order to minimize the strain on the yarn the spring which tends to move the indicating element to indicating position is preferably made as light as is consistent with reliable operation. As a result of this construction there is a chance that the detecting fingers may not have a sufficiently heavy contact with the indicator to establish a proper circuit. In order that the light pressure of the yarn may be coupled with the positiveness of indication I provide a holding device which is normally ineffective to restrain movement of the indicator and is held in non-locking position by the latter when yarn is present. At substantial exhaustion, however, the weak spring which exerts its pressure against the yarn is sufficiently strong to move the indicator or contact plate to a position where the lock may become effective to hold the contact plate against the downward pressure of the detecting element. The latter may therefore exert sufficient pressure to establish good contact.

With these and other objects in view which will appear as the description proceeds, my invention resides in the combination and arrangement of parts hereinafter described and set forth in the claims.

In the accompanying drawing, where a convenient embodiment of my invention is set forth,

Fig. 1 is a top plan view of a shuttle made according to my present invention,

Fig. 2 is a vertical section on line 2—2 of Fig. 1, showing the contact plate in two positions,

Fig. 3 is a transverse vertical section on line 3—3 of Fig. 2 showing the detector parts in detecting non-indicating position,

Fig. 4 is a diagrammatic view similar to Fig. 3 but showing the parts in detecting position when a sufficient supply of weft is present,

Fig. 5 is a view similar to a portion of Fig. 2

with the spindle raised and the detector retracted.

Fig. 6 is a top plan view of the shuttle box and detector.

5 Fig. 7 is a diagrammatic view showing how the lay motion is used to move the detector toward the shuttle, and

Fig. 8 is a view showing the contact plate locking means.

10 Referring to the drawing, I have shown a shuttle 10 which preferably may be adapted for silk weaving by a coating of fiber or like material 11, although this feature is not necessary. A transverse pin 12 forms the pivot of a spindle 15 having a vertical slot 14. The pin 12 extends through the wooden body 15 of the shuttle and may be held in position in any approved manner. The weft carrier 16 may be of metal and has a head 17 to coact with claws 18 on the shuttle 20 to hold the carrier against longitudinal and angular motion relatively to the spindle.

Pivoted to the spindle at 20 and extending within the slot 14 is a detector lever 21 having a rounded smooth upwardly extending detecting 25 surface 22 designed to project through a slot 23 in the carrier 16. As viewed in Fig. 2 the right hand end of said lever is curved upwardly and has mounted thereon a circuit closer or contact plate 24 which, as shown in Fig. 1, is 30 provided with a substantially long contact face 25 from the sides of which extend stop wings 26. A relatively weak coil spring 27 is interposed between the bottom of the contact plate and the spindle, and may be received in a 35 pocket 28 in the spindle.

The upper fiber plate of the shuttle preferably extends over the stop wings 26 as at 30 and serves to limit upward movement of the contact plate under influence of the spring. The 40 top fiber plate is also provided with an opening 31 to render the contact surface 25 accessible from above the shuttle. I do not wish to be limited to any particular form of weft carrier or means for holding the same in the shuttle, 45 inasmuch as it is sufficient for the operation of my present invention if the slot 23 is held in alignment with the detector surface 22 of the lever when the spindle is in normal lowered position.

50 The shuttle coacts with a pair of yieldable detector fingers or electrodes 40 and 41, respectively, each of which is formed as part of a ring 42 secured to a support 43 of insulating material rotatably mounted on a supporting 55 stud 44. The latter is held in a small stand 45 secured to the box back 46 of the loom. Interposed between the stud and the support 43 is a relatively light torsion spring 47 the effect of which is to move the electrode 41 down toward 60 the top of the shuttle. A collar 48 fixed to the opposite end of the stud receives one end of another light torsion spring 49 which is connected to the support 50 with the other electrode 40 tending to move the latter in the same direction as electrode 41. Collector brushes 51 and 52 contact respectively with the rings of electrodes 40 and 41. These brushes are mounted on an insulating base 53 carried by the lay and have electrical connection with mechanism not 65 shown to effect a change in loom operation whenever said brushes are electrically connected by the plate 24 at substantial exhaustion of weft.

70 As shown in Fig. 7 the lay L moves about the forward pivot 60 and there is provided a rear pivot 61 fixed with respect to the loom and hav-

ing mounted thereon an upwardly extending rod 62 which slides through a guide bearing 63 carried by and extending rearwardly from the lay. The upper end of this guide has a head 64 which extends laterally on each side of the rod 62 for engagement respectively with actuator arms 65 and 66 which are connected to the rings of electrodes 40 and 41, respectively. There is a sufficient space between the pivots 60 and 61 so that as the lay moves forwardly the cross head will have a relatively downward movement with respect to the lay and when the latter moves rearwardly the movement will be upward.

10 The head is so formed as to rock the electrodes in a clockwise direction as viewed in Fig. 3 when the lay moves backwardly, thereby raising the forward ends of the electrodes to keep them out of the path of the shuttle. On the forward beat of the lay, however, the relative downward movement of the head will move the latter away 20 from the actuator arms so that the springs 47 and 49 will move said arms downwardly after the shuttle is boxed. The top 70 of the head 64 will act as a stop for the arms 65 and 66 when no shuttle is present.

25 While I have shown a particular means for providing two electrodes which are each yieldingly movable toward the plate 24 when the lay is in front position and retracted or elevated to non-detecting position prior to pick of the shuttle, yet I do not wish to be limited to the particular mechanism shown.

30 In order to prevent closure of the electric circuit while the plate 24 is in low position I provide at least one of the electrodes, 41 as shown 35 herein, with a heel 75 which is placed so that it will engage the top of the shuttle and limit downward movement of the associated electrode. The other electrode may be similarly provided with a stop, but this is not essential, since the 40 holding of either electrode away from the plate will be sufficient to prevent contact when the plate is in low position.

45 Located on each side of the detector lever is a resilient stop or support 80 secured by screw 81 to a vertical wall 82 in the shuttle. Normally these supports are in the full line position, Fig. 8, lying against the wings 26.

50 In operation, as the lay moves forwardly with the shuttle on the detecting side of the loom the cross head will move out of control position with respect to the actuator arms and the springs 47 and 49 will move the electrodes down so that the ends of the latter will enter the slot 31 and move toward the top of the plate 55 25. If sufficient weft for continued weaving be present in the shuttle the detector arm 22 will be held down and the contact surface 25 will be located below the bottom of electrode 41. It will therefore be impossible to close the detector 60 circuit and the loom will continue to run. When weft is absent, however, except for the bunch 50, the detector surface 22 will no longer be restrained against upward movement under action 65 of the spring 27, and the contact surface will be raised as shown in dotted lines, Fig. 8, until the wings 26 engage the plate forming the top of the shuttle. The yielding supports 80 will then spring to the dotted line position of Fig. 8, 70 under the wings 26 to support the contact plate against downward pressure. Under these conditions, as the shuttle moves forwardly, the bottom of both electrodes will strike the contact plate to establish electrical connection between the 75

brushes 51 and 52, thereupon effecting a change in loom operation by mechanism not shown.

At indication, therefore, the spring 27 is not required to withstand the pressure of the electrodes, and said spring may therefore be made very light to reduce to a minimum pressure of the detecting surface against the weft.

It is to be noted that the heel 75 is so proportioned as to permit the corresponding detector to engage the surface 25 when the latter is raised, so that an external loom controlling circuit can be closed when the contact plate is raised.

When the shuttle is to be replenished it is removed from the loom and the spindle elevated to the position suggested in Fig. 5 the effect of which is to cause the wings 23 to be depressed against the action of the spring 27 by the overhanging parts 30 of the top of the shuttle. A reference to Figs. 1 and 2 will show that said wings are longitudinally spaced relatively to the spindle from the pivot of the latter sufficiently so that when said spindle is raised there is a downward movement of the contact surface 22 to permit the sliding and rotation of the carrier 16 on the spindle.

The placing of a fresh weft supply on the spindle depresses the detector plate, so that when the spindle is lowered, the contact plate returns toward the springs 80 in low enough position to strike said springs laterally and move them to the normal full line position shown in Fig. 8.

From the foregoing it will be seen that I have provided a form of shuttle and electric detector wherein that part of the detecting circuit which lies within the shuttle is very short and comprises a single member to have engagement with the two electrodes. By this arrangement of wires, binding posts and other forms of jointed circuit forming parts which have heretofore been employed are eliminated. Furthermore, the detector surface which engages these electrodes is on the top of the shuttle where it can never have contact with the binder or box back and assurance is therefore given that the grit and dirt which is a source of trouble where contact plates are located on the front and back walls of the shuttle will not be present in the shuttles shown herein. Although the part which gives indication to the external circuit moves in order to have direct contact with the electrodes, yet such moving part is located well within the outline of the shuttle and is therefore kept away from the threads of the top shed when the shuttle is in flight. It will be further noted that the springs 80 act to support or lock the contact plate in indicating position, so that spring 27 may be very light to prevent chafing of the weft.

Having thus described my invention it will be seen that changes and modifications may be made therein by those skilled in the art without departing from the spirit and scope of the invention and I do not wish to be limited to the details herein disclosed, but what I claim is:

1. In a loom, a shuttle having a supply of weft, a pair of oppositely charged electric detector electrodes separate from the shuttle to be connected to effect a change in loom operation, a shuttle carried contact member for the electrodes held out of contacting relation with the electrodes when sufficient weft is present and movable relative to the shuttle upon exhaustion of weft to a position to electrically connect said electrodes, by direct engagement therewith, the

electrodes mounted to be movable toward and from the contact member, and a stop to limit relative movement of the contact member toward the electrodes.

2. In a loom, a weft detecting shuttle, a pair of oppositely charged detecting electrodes, said shuttle having a spindle, a lever pivoted to the spindle, a contact member carried by the lever, the shuttle having an opening to expose the contact member and render the latter accessible from without the shuttle, a yarn engaging weft detector on the lever, and means to move the contact member toward the electrodes, a sufficient amount of weft for continued weaving engaging the weft detector to prevent such movement, and said means effective to move the contacting member into engaging position relatively to the electrodes at exhaustion of weft.

3. In an electrically operating weft detecting shuttle, a contact member located within the outline of the shuttle and normally held by a sufficient supply of weft out of indicating position relatively to the shuttle, lock means tending normally to move in a direction substantially parallel to the shuttle to a position to lock the contact member in indicating position but restrained from such movement by said contact member when sufficient weft is present, and means effective upon weft exhaustion to move the contact member to indicating position and render said lock means effective to move to a position to lock the contact member against movement away from the indicating position.

4. In an electrically operating weft detecting shuttle a contact member movable vertically in the shuttle and held by sufficient weft in down position, lock means tending to move longitudinally of the shuttle to a position under the contact member to lock the latter in raised indicating position, the contact member preventing movement of the lock when sufficient weft is present, and means effective upon exhaustion of weft to raise the contact member into indicating position, the lock thereupon being effective to move under the contact member and lock the same in raised position.

5. In an electrically operating weft detecting shuttle a weft supporting spindle pivoted to the shuttle, a detecting element supported by and movable relatively to the spindle, a contact member carried by the element and held out of indicating position by a sufficient supply of weft, a yieldable lock to engage a part of the contact member tending to move in a direction parallel to the spindle into holding relation relatively thereto, and means effective upon exhaustion to move the contact member into indicating position with respect to the shuttle, the lock thereupon moving to a position to support the contact member.

6. In a loom, a shuttle having a supply of weft, a shuttle carried contact member held out of indicating position when sufficient weft is present and movable relatively to the shuttle upon exhaustion of weft to indicating position, a pair of oppositely charged electric detector electrodes mounted independently of the shuttle, one of said electrodes having a part to engage the shuttle to prevent said one electrode from engaging the contact member when the latter is out of indicating position, and both of said electrodes having parts to engage the contact member when the latter is in indicating position, and means to move said electrodes toward the shuttle on detecting beats of the loom to engage either the

shuttle or the contact member depending upon the condition of weft in the shuttle.

- 5 7. In a loom, a shuttle having a supply of weft, a pair of oppositely charged electric detector electrodes mounted independently of the shuttle to be connected to effect a change in loom operation, a shuttle carried contact member for the electrodes held in non-indicating position when sufficient weft is present and movable relatively to the shuttle upon substantial exhaustion of weft to indicating position, each electrode having a part to contact with the contact member when the latter is in indicating position and at least one of said electrodes having a part to contact with the shuttle and be held out of engagement with the contact member when the latter is in non-indicating position, and means to move said electrodes toward the shuttle and contact member on detecting beats of the loom, said contact member being the only current carrying part permanently connected to the shuttle.
- 10 8. In a loom, a shuttle having a supply of weft, a pair of oppositely charged electric detector electrodes mounted independently of the shuttle to be connected to effect a change in loom operation, a shuttle carried contact member for the electrodes held out of contacting relation with the electrodes when sufficient weft is present and movable relatively to the shuttle upon exhaustion of weft to a position to electrically connect said electrodes, and means to move the

electrodes toward the contact member and shuttle on detecting beats of the loom.

- 15 9. In an electrically operating weft detecting shuttle, a spindle on the shuttle to support a mass of weft, a detecting lever supported by and movable with respect to the spindle, a weft detector contacting plate carried by the detecting lever, presence of sufficient weft effective to hold the contact plate out of indicating position with respect to the shuttle, means to move the contact plate into indicating position relatively to the shuttle upon substantial exhaustion of weft, and means normally urged against the plate in a direction substantially parallel to the spindle to thereafter prevent said contact plate from 15 moving relatively to the shuttle and away from indicating position.

- 20 10. In an electrically operating weft detecting shuttle, a contact member carried by the shuttle and movable with respect thereto and held by a sufficient supply of weft out of indicating relation with respect to the shuttle, means effective upon exhaustion of weft to move the contact member relatively to the shuttle into indicating position, and means normally urged against the 25 contact member in a direction longitudinally of the shuttle and tending to move under said contact member to lock the latter in indicating position.

RICHARD GREENLEAF TURNER. 30
